BOXED PRODUCE CARLOADING

Harold C. Pierce, Pomona, Calif.

Application October 23, 1945, Serial No. 624,008

17 Claims. (Cl. 105—367)

1
This invention has to do with the loading of boxed produce in refrigerator cars, and particularly with loads or kinds of produce, such as grapes, where the boxes are placed bottom down and arranged in stacks laid in rows extending transversely and longitudinally within the car.

One of my primary objects is to depart from conventional practices by the provision of a new form of load characterized by its capacity, after being refrigerated at the point of shipment, to reach its destination at a substantially lower temperature than has been possible in the employment of load forms heretofore used. In this respect, the invention aims to provide for locations and degrees of spacing between the box stacks that will permit cold air circulation for efficient initial refrigeration of the load, and yet maintain the stacks in such compact or interengaged relation as to minimize their absorption of heat during transit should the temperature of the car for any reason tend to rise above normal refrigeration temperatures.

Considering typically the conventional grape load, a common practice is to space apart both the transverse and longitudinal rows, so that each stack is surrounded by an air space. While favoring rapid cooling of the load, the exposures of the individual stacks is conducive to relatively rapid heating or loss of refrigeration.

In accordance with the invention, the boxes as arranged in the car are placed in side-to-side engagement to eliminate any spacing, or any appreciable spacing, in the transverse rows, so that with respect to their thermal characteristics, all the boxes in each transverse row approach a single mass. Only the boxes in the longitudinal rows are spaced apart, or in other words, the continuous transverse rows are spaced apart, and the spacing is predetermined to permit adequate air circulation for initial refrigeration, but without excessive spacing conducive to heating in transit.

A further object is to provide an improved bracing system for strongly supporting and maintaining the load in the condition described. For this purpose I employ a novel type of spacer and brace assembly adapted to be interposed between the transverse rows, and between the outside of the load and the car walls, individual units of the spacer and brace assembly being applicable progressively to the exposed inner ends of the load as it is built toward the center of the car.

In this connection, a feature of particular importance is an improved type of spacer unit

2
adapted to extend vertically between and in overlapping relation with opposed pairs of box stacks, and carrying or having associated therewith, projections preventing lateral shifting of the spacer members and of such proportions as to extend between interengaging sides of the boxes.

All the aforementioned features and objects, as well as the details of certain illustrative embodiments of the invention, will be understood to better advantage from the description to follow. Reference is had to the accompanying drawings, in which:

Fig. 1 is a cross-section taken transversely through the car and load incorporating one embodiment of the invention;

Fig. 2 is a fragmentary side view of the load taken on line 2—2 of Fig. 1;

Fig. 3 is a fragmentary plan section on line 3—3 of Fig. 1;

Fig. 4 is a fragmentary view taken in the aspect of Fig. 1, showing a variational and preferred form of load and brace system;

Fig. 5 is a fragmentary side elevation of the load taken on line 5—5 of Fig. 4;

Fig. 6 is a fragmentary enlargement of one of the side supports or braces;

Fig. 7 is an enlarged fragmentary section on line 7—7 of Fig. 4;

Fig. 8 is a view similar to Fig. 6 illustrating a further variational form of the invention; and

Fig. 9 is a cross-section taken on line 9—9 of Fig. 8.

Referring first to Figs. 1 to 3, the box load generally indicated at 10 is shown to be contained within a refrigerator car having the conventionally illustrated side walls 11 and floor 12. The load 10 is shown to comprise individual stacks S, typically of grape or like boxes 13 arranged bottom down and in vertical alignment within the individual stacks. The stacks S are aligned in rows R running transversely of the car and also in rows longitudinally of the car, i. e. normal to the plane of Fig. 1, as will be readily understood. The ends of the boxes 13 in adjacent stacks S and in the transverse rows R are in end engagement, or substantially so, although for clarity of illustration and distinction of adjacent box stacks, the dotted lines in Fig. 1 show the box ends to be spaced slightly. As previously indicated, in so placing the boxes in end engagement, my primary object is to maintain the load in a condition of maximum compactness transversely of the car.

The individual boxes may be of any of the

conventional types used in shipping grapes, tomatoes and the like, and which are so constructed that when arranged in a stack, the interiors of the boxes and contained produce are accessible to treating gases or cooling air at their sides 54, but not at their closed ends 52. For simplicity of illustration, the boxes have been typically represented as of a known type having uncovered upper sides through which gases and air may gain access to the contained produce. Each box has, at its opposite ends, the usual upwardly projecting lugs 51 extending across the upper edges of its end walls 52 and upon which the next higher box in the same stack rests. As will be appreciated, these lugs act as spacers to form air circulation spaces 53 between the transversely extending side walls 54 of the boxes through which air enters the sides of the stacks for access to the produce through the open upper sides of the boxes. At the same time, the lugs act as upper continuations of the end walls 53, so that the end walls in each stack are in continuous vertical sequence.

The transverse rows are spaced apart and the boxes and stacks in each transverse row are maintained and supported in proper condition by the following described assembly adapted to be interposed between successive transverse rows as the load is built in the car from its end to the center. The spacing and bracing assembly comprises plurality of intermediate braces or boards 14 (e. g. $\frac{3}{4}$ " x 3") extending vertically from the floor the full height of the stacks S and bearing against and overlapping the sides of adjacent stacks at their engaging ends. At their outer ends, the transverse rows are spaced apart by T-shaped spacers 15 co-extensive in height with the intermediate braces 14 and made up preferably of a $\frac{3}{4}$ " x 3" spacer 16 received between and spacing apart the transverse rows R, as shown in Fig. 3, and members 17 nailed to the spacer part 16 and bearing against the outer ends of the boxes 13. Thus the transverse rows R are spaced apart at 18 a distance corresponding to the thickness of members 14 and 16, which typically may be in the neighborhood of $\frac{3}{4}$ ", as indicated.

Members 14 and the end assemblies 15 are interconnected by transverse metal straps 19 and 20 attached to members 14 by staples 21 and 22 at their ends to the assemblies 15, as by bringing the ends of the straps about the outside of the spacer 16 so that the straps are securely held in place by members 17. One particular feature and object of the invention is to obviate in a simple manner the possibility of lateral shifting of the members 14 away from their proper and intended overlapping relation with the adjacent end portions of the boxes. This result is accomplished by inserting or driving through the members 14 rigid metal projections 22, preferably of sufficiently small size or thickness to be receivable between adjacent boxes 13 while permitting inter-engagement of the box ends. In the showing of Fig. 2 (and also of Fig. 5) the box stack S1 in row R1 is assumed for purposes of illustration to be removed in order to expose the projections 22 (and 31) inside the load. As illustrated in Fig. 2, the projections 22 preferably extend beyond both faces of the members 14 so as to be receivable between the ends of the boxes in adjacent though spaced transverse rows R.

The described load assembly may be confined within a predetermined lateral dimension inside

the car, by nailing to the car floor, strips 23 running longitudinally thereof at the outside of the load so as to be engageable by the end spacer units 15. The load may be suitably braced from the side walls 11 of the car by vertically extending spacer boards 25 nailed to the car.

The spacer and support assembly consisting of the end units 15, members 14, straps 19 and the projections 22, individually may be made up and assembled as units for application to successive transverse box rows as they are filled into the car. Thus assuming a transverse row R has been placed in the car, the indicated assembly may be put in place and applied to the boxes in the condition shown in Fig. 1, with the projections 22 inserted between adjacent ends of the boxes then in place. The next box row R is then put in place against the spacing and brace assembly, with the projections 22 received between the ends of the last placed boxes. The entire load is thus filled into the car in this manner, from the car ends toward the center, and finally may be subjected to the usual squeezing operation to compact the load longitudinally of the car and open the center space for bracing or the insertion of boxes finally to be put into the car. The entire load may be stabilized and integrated by applying and tensioning steel straps 50 about the sides and ends of the load.

The car and load thus are ready for refrigeration which is accomplished by the usual means, not shown, acting to maintain a flow of cold air through the spaces 18 until the load is brought down to proper temperature. It will be noted that by reason of the compacted box arrangement transversely of the car, heat gain after refrigeration is confined (other than at the top and outside of the load) to the exposures at space 18, and therefore the rate of heat gain necessarily is considerably lower than in conventional loads for produce of this type, where the individual box stacks are spaced both at their sides and ends.

Considering now the variational form shown in Figs. 4 to 7, the arrangement and relationship of the boxes are exactly the same as in the first described load. One differentiating characteristic of the variational form is that it dispenses with the use of transverse straps between the rows R. Referring to Fig. 4, as in the previous instance vertical braces 30 are interposed between the rows R against and in overlapping relation with the end portions of adjacent stacks. Here the projections corresponding to elements 22 in Fig. 2 consist of thin but rigid metal plates 31 inserted through slots 32 in member 30 and held in position by interengagement of the plate notch 33 with the bottom of the slot. The projections 31 are easily made and installed, and effectively prevent lateral shifting of the members 30. The end spacer and brace units 34 correspond in structure and function to the previously described units 15. The load is laterally positioned at the floor by the strips 35 and is supported and spaced from the car wall 11 by braces 36 running longitudinally of the car in overlapping relation with successive box rows R, it being understood that any suitable number of the braces 36 may be used serially to so support and space the load throughout its length. Each brace 36 is attached at suitable intervals to blocks 37 nailed to or merely bearing against the car wall, in which latter event the brace and block assembly is supported on small blocks 38 nailed to the units 34. If de-

sired, steel straps, not shown, may be applied to and tightened about the outside of the entire load as an aid to its stabilization and integration.

Figs. 8 and 9 illustrate a further variational feature in the provision of spacer and bracing means that are self-acting to compensate for any looseness or variation that may develop in the spacing of the load from the car side wall. Here blocks 46 applied to the units 34 support a brace 44 extending along and in overlapping relation with the successive transverse box rows R. The brace 44 is engaged by a gravity wedge assembly 42 consisting of a base 43 bearing and slidably vertically against the car wall 11, and carrying the wedge proper 44, the inclined edge of which engages member 41. As will be understood, any suitable number of the wedge assemblies 42 may be used along the length of member 41. Enlargement of the space at 45 between the load and car wall, resulting for example from transverse compacting of the load, results in downward movement of the wedge assembly so that the latter at all times maintains a rigid support for the load from the one wall.

I claim:

1. A boxed produce load for refrigerator cars comprising boxes arranged bottom down in vertical stacks and alined in stacked rows running transversely and longitudinally of the car, the longitudinal walls of the boxes in adjacent longitudinal rows being in engagement and said walls being closed and in substantially continuous vertical sequence in each stack, and means inserted between and spacing apart the transverse rows to provide for air circulation therebetween, there being air spaces between the vertically successive transverse sides in each stack exposed to the air circulation space between said transverse rows.

2. A boxed produce load for refrigerator cars comprising boxes arranged bottom down in vertical stacks and alined in stacked rows running transversely and longitudinally of the car, the longitudinal walls of the boxes in adjacent longitudinal rows being in engagement and said walls being closed and in substantially continuous vertical sequence in each stack, and vertically extending spacer members inserted between and spacing apart adjacent transverse rows, there being open air spaces between said members and extending from the floor of the car to the top of the box load, and there being air spaces between the vertically successive transverse box sides in each stack exposed to said air spaces between said members.

3. A boxed produce load for refrigerator cars comprising boxes arranged bottom down in vertical stacks and alined in stacked rows running transversely and longitudinally of the car, the longitudinal walls of the boxes in adjacent longitudinal rows being in engagement and said walls being closed and in substantially continuous vertical sequence in each stack, spacer members extending vertically between transverse rows and engaging and overlapping the transverse walls of opposed pairs of the individual box stacks at opposite sides of their engaging walls to provide for air circulation between said transverse rows, there being air spaces between the vertically successive transverse box sides in each stack exposed to the air circulation spaces between said transverse rows, and means preventing shifting of said spacer members laterally of the car.

4. A boxed produce load for refrigerator cars comprising boxes arranged bottom down in vertical stack and alined in stacked rows running

transversely and longitudinally of the car, the longitudinal walls of the boxes in adjacent longitudinal rows being in engagement and said walls being closed in substantially continuous vertical sequence in each stack, spacer members extending vertically between transverse rows and engaging and overlapping the transverse walls of opposed pairs of the individual box stacks at opposite sides of their engaging walls, and projections extending from said members between said stacks to prevent shifting of said spacer members laterally of the car and sufficiently thin to permit engagement of the longitudinal box walls between which they are received, there being spaces between the vertically successive transverse box sides in each stack through which air from between the transverse row may flow into the boxes.

5. A boxed produce load for refrigerator cars comprising boxes arranged bottom down in vertical stacks and alined in stacked rows running transversely and longitudinally of the car, the longitudinal walls of the boxes in adjacent longitudinal rows being in engagement and said walls being closed in substantially continuous vertical sequence in each stack, vertically extending spacer members inserted between and spacing apart adjacent transverse rows, there being open air spaces between said members and extending from the floor of the car to the top of the box load, there being spaces between the vertically successive transverse box sides in each stack through which air from said air spaces between the members may flow into the boxes, and a metal strap extending between said transverse rows and attached to said spacer members.

6. A boxed produce load for refrigerator cars comprising boxes arranged bottom down in vertical stacks and alined in stacked rows running transversely and longitudinally of the car, the longitudinal walls of the boxes in adjacent longitudinal rows being in engagement and said walls being closed in substantially continuous vertical sequence in each stack, spacer members extending vertically between transverse rows and engaging and overlapping the transverse walls of opposed pairs of the individual box stacks at opposite sides of their engaging walls, a metal strap extending between said transverse rows and attached to said spacer members, and projections extending from said members between said stacks to prevent shifting of said members laterally of the car and sufficiently thin to permit engagement of the longitudinal box walls between which they are received, there being spaces between the vertically successive transverse box sides in each stack through which air from between the transverse rows may flow into the boxes.

7. A boxed produce load for refrigerator cars comprising boxes arranged bottom down in vertical stacks and alined in stacked rows running transversely and longitudinally of the car, the longitudinal walls of the boxes in adjacent longitudinal rows being in engagement and said walls being closed in substantially continuous vertical sequence in each stack, spacer members extending vertically between transverse rows and engaging and overlapping the transverse walls of opposed pairs of the individual box stacks at opposite sides of their engaging walls, there being open air spaces between said members and extending from the floor of the car to the top of the box load, there being spaces between the vertically successive transverse box sides in each stack through which air from said air spaces be-

tween the members may flow into the boxes, a metal strap extending between said transverse rows and attached to said spacer members, and vertically extending outer spacer members attached to said strap and placed against the car side walls and in overlapping relation with the ends of adjacent transverse rows.

8. A boxed produce load for refrigerator cars comprising boxes arranged bottom down in vertical stacks and alined in stacked rows running transversely and longitudinally of the car, the longitudinal walls of the boxes in adjacent longitudinal rows being in engagement and said walls being closed in substantially continuous vertical sequence in each stack, spacer members extending vertically between transverse rows and engaging and overlapping the transverse walls of opposed pairs of the individual box stacks at opposite sides of their engaging walls, and rigid projections, short as compared with the box length, carried by said members and projecting between the longitudinal box walls of said stacks, said projections being sufficiently thin to permit engagement of the box walls between which they are received, there being open air spaces between said members and extending from the floor of the car to the top of the box load, and there being spaces between the vertically successive transverse box sides in each stack through which air from said air spaces between the members may flow into the boxes.

9. A boxed produce load for refrigerator cars comprising boxes arranged bottom down in vertical stacks and alined in stacked rows running transversely and longitudinally of the car, the longitudinal walls of the boxes in adjacent longitudinal rows being in engagement and said walls being closed in substantially continuous vertical sequence in each stack, spacer members extending vertically between transverse rows and engaging and overlapping the transverse walls of opposed pairs of the individual box stacks at opposite sides of their engaging walls, and individual thin metallic projections carried by said members and projecting therefrom between the stacks, said projections being sufficiently thin to permit engagement of the box walls between which they are received, there being open air spaces between said members and extending from the floor of the car to the top of the box load, and there being spaces between the vertically successive transverse box sides in each stack through which air from said air spaces between the members may flow into the boxes.

10. For use in stabilizing a boxed produce load comprising boxes alined in stacked rows transversely and longitudinally of the car, a spacer member extending vertically between transverse rows and engaging and overlapping the transverse walls of opposed pairs of individual box stacks at opposite sides of the longitudinal walls of said stacks, and a projection extending from said member to be received between the longitudinal walls of said stacks and sufficiently thin to permit engagement of said walls between which the projection is received.

11. For use in stabilizing a boxed produce load comprising boxes alined in stacked rows transversely and longitudinally of the car, a spacer member extending vertically between transverse rows and engaging and overlapping the transverse walls of opposed pairs of individual box stacks at opposite sides of the longitudinal walls of said stacks, and an element extending through and projecting centrally from said member to be received

8
received between the longitudinal walls of said stacks, said element being sufficiently thin to permit engagement of the walls between which it is received.

5 12. For use in stabilizing a boxed produce load comprising boxes alined in stacked rows transversely and longitudinally of the car, a spacer member extending vertically between transverse rows and engaging and overlapping the transverse walls of opposed pairs of individual box stacks at opposite sides of the longitudinal walls of said stacks, and a thin metallic element retained within a slot in said member and projecting therefrom to be received between the longitudinal walls of said stacks, said element being sufficiently thin to permit engagement of the walls between which it is received.

13. For use in stabilizing a boxed produce load comprising boxes alined in stacked rows transversely and longitudinally of the car, a spacer member extending vertically between transverse rows and engaging and overlapping the transverse walls of opposed pairs of individual box stacks at opposite sides of the longitudinal walls of said stacks, and a pair of vertically spaced notched metallic elements inserted through and retained within vertical slots in said member, said elements projecting centrally from the member to be received between the longitudinal walls of said stacks and being sufficiently thin to permit engagement of the walls between which they are received.

14. For use in stabilizing a boxed produce load comprising boxes alined in stacked rows transversely and longitudinally of the car, a prefabricated unit spacer assembly comprising a plurality of spacer members to extend vertically between adjacent transverse rows and individually engaging and overlapping the transverse walls of opposed pairs of individual box stacks at opposite sides of the adjacent longitudinal walls of said stacks, a flexible metal strap attached to said members and adapted to extend between said transverse rows, and vertically extending spacer members connected to the ends of said strap and adapted to be interposed between the car side walls and the ends of said transverse rows.

15. For use in stabilizing a boxed produce load comprising boxes alined in stacked rows transversely and longitudinally of the car, a prefabricated unit spacer assembly comprising a plurality of spacer members to extend vertically between adjacent transverse rows and individually engaging and overlapping the transverse walls of opposed pairs of individual box stacks at opposite sides of their longitudinal walls, a flexible metal strap attached to said members and adapted to extend between said transverse rows, vertically extending spacer members connected to the ends of said strap and adapted to be interposed between the car side walls and the ends of said transverse rows, and rigid metallic projections carried by and extending from the first mentioned members and adapted to be received between said stacks said projections being sufficiently thin to permit engagement of the longitudinal walls between which they are received.

16. A boxed produce load for refrigerator cars comprising boxes arranged bottom down and alined in stacked rows running transversely and longitudinally of the car, the longitudinal walls of the boxes in adjacent longitudinal rows being in engagement, means inserted between and spacing apart the transverse rows to provide for air circulation therebetween, outer spacing means

maintaining the load in spaced relation to the car side wall, said outer spacing means comprising a wedge member movable downwardly by gravity to take up looseness in the load spacing.

17. A boxed produce load for refrigerator cars comprising boxes arranged bottom down and alined in stacked rows running transversely and longitudinally of the car, the longitudinal walls of the boxes in adjacent longitudinal rows being in engagement, means inserted between and spacing apart the transverse rows to provide for air circulation therebetween, outer spacing means maintaining the load in spaced relation to the car side wall, said outer spacing means comprising a member extending longitudinally of the car in overlapping relation with the ends of a succession of said transverse rows, and a wedge member movable downwardly by gravity between the last mentioned member and the car side wall to take up looseness in the load spacing.
